UNITED STATES PATENT OFFICE

99,614

DESIGN FOR A SAW GAUGE

Herbert E. Tautz, Milwaukee, Wis., assignor to
Delta Manufacturing Company, Milwaukee,
Wis.

Application March 2, 1936, Serial No. 61,452

Term of patent 14 years

To all whom it may concern:

Be it known that I, Herbert E. Tautz, a citizen of the United States, residing at 620 East Vienna Avenue, in the county of Milwaukee and State of Wisconsin, have invented a new, original, and ornamental Design for Saw Gauges, of which the following is a specification, reference being had to the accompanying drawing, forming part thereof.

The figure is a perspective view of a saw gauge, embodying my new design.

The dominant feature of the design resides in the head portion of the gauge.

I claim:

The ornamental design for a saw gauge, as shown and described.

HERBERT E. TAUTZ.
